UNITED STATES PATENT OFFICE.

MARSHALL B. LLOYD, OF MENOMINEE, MICHIGAN.

METHOD OF AND MEANS FOR BINDING THE EDGES OF REED FABRIC AND THE LIKE.

1,336,571.

Specification of Letters Patent. Patented Apr. 13, 1920.

Application filed May 28, 1917. Serial No. 171,432.

To all whom it may concern:

Be it known that I, MARSHALL B. LLOYD, a citizen of the United States, and a resident of Menominee, Michigan, have invented 5 a certain new, useful, and Improved Method of and Means for Binding the Edges of Reed Fabric and the like, of which the following is a specification.

The fabric with which my invention is 10 particularly concerned is composed of a plurality of spaced members called stakes which may be of reed or wire upon which long strands called fillers are woven over some of the stakes and under others.

15 The fabric to which this invention relates is for use in the construction of baby carriages and furniture.

The general object of my invention is to 20 provide a method whereby the free ends of such fabric can be easily and quickly secured against undesired separation to the end that the fabric shall permanently retain its shape and character.

Further objects of my invention are to 25 provide a method of finishing or binding the free ends of reed fabric which shall be of pleasing appearance, of low cost, which will admit of the fabric being conveniently placed upon and secured to desired frames 30 or articles; which shall not injure the fabric, which shall impart added stability to the fabric, and which shall enable the use of separate pieces of fabric where under prior methods it has been necessary to weave 35 the fabric upon and secure it directly to the frame or article.

My invention consists generally in the step, acts and means whereby the above named objects, together with others which 40 will appear hereinafter are attainable and my invention will be more readily understood by reference to the accompanying drawings illustrative thereof.

In said drawings:

45 Figure 1 is a side elevation of a tubular woven reed fabric.

Fig. 2 is a plan view of the fabric shown in Fig. 1.

Fig. 3 illustrates the fabric of Figs. 1 and 50 2 after it has been severed to form a strip.

Fig. 4 is an enlarged edge view of the fabric illustrating its character.

Fig. 5 illustrates, in perspective, a portion of strip metal such as I may use for 55 binding purposes.

Fig. 6 is an edge view of the metal of

Fig. 5 partially formed to form an edge binder.

Fig. 7 illustrates a further step in the operation, the edge of the fabric being inserted in the partially formed binder. 60

Fig. 8 is a view illustrating the finished product; and

Fig. 9 is a view of the fabric of Fig. 3 with the edge binders thereon. 65

In the drawings 1 illustrates a tubular reed fabric composed of filler strands 2 and spaced stakes 3. Reed fabric is made in many ways but the most common type is that in which the filler strands pass over 70 and under alternate stakes as depicted in the drawings. I wish it to be understood, however, that my invention is not concerned with the character of the weave which may be varied as desired. 75

In Figs. 1 and 2 I have shown a tubular fabric such as I find it convenient to weave and which may be utilized for many purposes. The tubular fabric is severed as along the line $x-x$ (Fig. 2) thus producing a strip 80 of fabric as shown in Fig. 3. This operation results in leaving a large number of free or loose ends 4 of the filler strands. In this condition the filler strands are easily separated from the stakes and the fabric must be carefully handled or it is likely to separate. If the fabric be in this condition placed upon a frame or other article as a covering all or a large number of the separate filler strand ends must be secured to the frame or article. 85 90 This operation is a slow and laborious one and results in an unsightly product. Furthermore when the fabric is placed in some places upon certain articles it is difficult to tack or fasten the various filler strands in 95 place because of the limited amount of room. Again it may be desirable to manufacture the fabrics in one place and ship them to remote places for assembly upon or security to frames or articles. 100

I have devised a simple and inexpensive method and means whereby the fabric edge can be held against undesired separation and which will simplify the manufacture of reed articles either contiguous the point of 105 manufacture of the reed fabric or at points remote therefrom. To this end I provide a strip of material 10, see Fig. 5 which is fairly rigid but which can be shaped or formed to provide a channel in which the 110 loose or free ends of the filler strands can be placed. I have so far found relatively

light sheet metal to be the best material for this purpose, although a very thin sheet of metal with a covering of paper or other fiber may be also used. One of the principal characteristics desired is that the material be readily formed yet of such rigidity as to bind the fabric into a fairly permanent unit. I first form the sheet metal 10 back upon itself thus forming the portion 12. In this manner I provide a groove or channel 13 of a size sufficient to accommodate the filler strands of the fabric as illustrated in Fig. 7. After the free or loose end of the filler strands are placed in position I fold the metal back upon itself which firmly and securely binds and presses the filler strand ends between the metallic folds. Thus the fabric becomes a unit practically as non-separable as it was when in tubular form. The fabric with the binder edges is depicted in Fig. 9 wherein 15 are the metallic binders. The fabric in this condition can be freely and roughly handled without danger of causing its separation. Furthermore it can be readily fastened to or upon an article or frame by driving a relatively few fastening devices through the metallic edge or binder. Reed, both natural and the so called fiber reed, will break if too abruptly bent or kinked especially if in relation to a relatively sharp firm metallic edge. If the filler strand ends were broken or severed when fastening the binder thereto they would be likely to pull out if subjected to a strain as they might and would be in certain articles, as for example a chair seat. I obviate practically all danger of breaking or severing the fabric by the novel way in which I form the binder. To this end note that the end portion 12, around which the fabric filler strands are bent during the binding operation, is rounded as at 20, thus presenting a smooth surface around which the filler strands are drawn. In fact as I prefer to form the metallic binder there are no sharp edges to cut or injure the fabric and the

outer surfaces are also smooth and slightly. It will be understood that the detail views are somewhat exaggerated to bring out clearly the relation of the parts and the disposition of the metal.

It should also be understood that my method of finishing or binding the fabric edge is useful and may be employed whether the fabric is produced in tubular or endless form and then severed, or whether it be produced in other way if there be loose or free ends to be secured. It should also be understood that a binder of the class described may be used in like manner if desired to bind the projecting stake ends. This is such an obvious fact that it is not thought necessary to illustrate or describe same in detail. In fact the operation will be practically identical except that the stake ends are placed in the channel 13, instead of the filler strands.

I claim:

1. A binder for reed fabric and the like, comprising a metallic strip in which a longitudinal portion is folded back in spaced relation to the remainder of the strip thereby forming a groove for the reception of fabric, and in which the edge portion of that part of the strip which is folded back is reversely folded to form a rounded edge.

2. As a new article of manufacture a woven fabric of reed-like character having an edge portion bounded by a metallic strip, a portion of which is folded longitudinally so as to inclose the fabric edge portion, said folded strip portion being reversely folded along its edge to form a rounded edge portion, and the inclosed fabric and folded strip portion being folded back upon the fabric.

In testimony whereof I hereunto set my hand, this 9th day of May, 1917, in the presence of two subscribing witnesses.

M. B. LLOYD.
